D. L. Gibbs

United States Patent Office.

D. L. GIBBS, OF WORCESTER, MASSACHUSETTS.

Design No. 3,189, dated September 1, 1868.

DESIGN FOR BASE OF A MORTISING-MACHINE.

The Schedule referred to in these Letters Patent and making part of the same.

KNOW ALL MEN BY THESE PRESENTS:

That I, D. L. GIBBS, of the city and county of Worcester, and Commonwealth of Massachusetts, have invented a new and original Design for Base of Mortising-Machines; and I do hereby declare that the following is a full, clear, and exact description of the same, reference being had to the accompanying drawings, forming a part thereof, and in which—

Figure 1 represents a perspective view of my new and original design for base of mortising-machines, and Figure 2 represents a top or plan view thereof.

The upper part is made with sides, A, and rounded corners, B, at the bottom of which is the moulding or part, C, while below that is the square part, D; then another moulding or part, E, and then the lower part, F, from which project the peculiar-shaped feet G G G G.

My design is quite ornamental, attractive to the eye, and adds very much to the looks of the machine.

What I claim as my invention, and desire to secure by Letters Patent, is—

The design for the base of a mortising-machine, as herein described, and shown in the accompanying drawings.

D. L. GIBBS.
